TERMINAL CAP FOR A MOTION PICTURE SCREEN SUPPORT

Russell E. Petrick, Park Ridge, Ill.

Application February 19, 1954, Serial No. 29,124

Term of patent 14 years

(Cl. D61—1)

Fig. 1.

Fig. 2.

Fig. 4.

Fig. 3.

Fig. 5.

To all whom it may concern:

Be it known that I, Russell E. Petrick, a citizen of the United States, residing at Park Ridge, county of Cook, and State of Illinois, have invented a new, original, and ornamental Design for a Terminal Cap for a Motion Picture Screen Support, of which the following is a specification, reference being had to the accompanying drawing, forming a part thereof, in which:

Figure 1 is a side elevational view of a terminal cap for a motion picture screen support embodying my new design;

Figure 2 is a rear elevational view;

Figure 3 is a front elevational view;

Figure 4 is a top plan view; and
Figure 5 is a bottom plan view.

I claim:

The ornamental design for a terminal cap for a motion picture screen support, as shown.
